UNITED STATES PATENT OFFICE.

ARNOLD SCHWIEGER, OF BERLIN, GERMANY.

PRESS FOR THE MANUFACTURE OF TUBES, RODS, AND THE LIKE FROM BLANKS.

No. 924,005.

Specification of Letters Patent.

Patented June 8, 1909.

Application filed June 27, 1907. Serial No. 381,162.

To all whom it may concern:

Be it known that I, ARNOLD SCHWIEGER, engineer, a subject of the German Emperor, and residing at No. 36 Stralauer Allee, Berlin, in the Kingdom of Prussia and German Empire, have invented certain new and useful Improvements in Presses for the Manufacture of Tubes, Rods, and the Like from Blanks, of which the following is a specification.

This invention relates to an improved press for the manufacture of tubes, rods and the like from blanks in the form of blocks.

The improved press differs from the known presses of the kind in the novel construction and arrangement of the operative parts as will hereinafter be described and claimed.

The improved press can be used for a greater variety of work, and with less expenditure of power and less wear than those hitherto in use.

A construction embodying the invention is illustrated in the annexed drawings, in which—

Figure 1 is a vertical section of that portion of the press which must be shown in order to illustrate the invention. Fig. 2 is a horizontal section of the expelling device and matrix block, Fig. 3 a cross-section on the line A—B of Fig. 2, and Fig. 4 an end view of the matrix block. Figs. 5 and 6 are longitudinal sections of a portion of the press on a larger scale, and Fig. 7 shows a detail on a still larger scale. Figs. 8 to 16 are sections of tubes, and Figs. 17 to 21 illustrate a modification of the connection between the matrix-locking mechanism and the abutment for the die, Figs. 20 and 21 being sections on the lines C—D and E—F of Fig. 19. Figs. 22 to 27 show a special form of abutment device, Fig. 26 being a section on the line G—H of Fig. 23.

The presser piston 1 is prolonged in the known manner by a die 2 traversed by a mandrel 3. The latter can be advanced independently of the die. Opposite the die is the press chamber 4, to which is joined the matrix 5 which is held in position by the holder 7 mounted on the matrix block 6.

Whereas it has hitherto been usual for the press disk 8 in front of the die 2 to fit closely around the mandrel 3, the present invention provides an aperture which leaves an annular chamber 9 between the inner wall and the mandrel (Figs. 5 and 6), which chamber may

be enlarged at the rear 10. The mandrel itself is slightly coned throughout its effective length. The diameter of the mandrel at the front end exceeds the diameter of the aperture of the matrix, so that only a tapered portion of the mandrel, the form-point 11 (Figs. 5 to 7) can be more or less inserted into the matrix.

On starting the pressing operation (Fig. 5) the annular space between the disk 8 and mandrel 3 allows a small quantity of the material pressed to form a sheath around the mandrel, on which the said material hardens. As the operation proceeds, that is to say as the die 2 advances in the manner shown in Fig. 6, this sheath is continuously added to, since the material tends to fill up the space 9, the capacity of which continuously increases by reason of the tapering shape of the mandrel. Injurious friction between the mandrel and disk and between the mandrel and material is thus obviated; in ordinary presses this friction rapidly wears away the mandrel and frequently increases to an extent which causes fracture. The enlarged part 10 of the chamber enables the sheath surrounding the mandrel to expand and to become loose on the rear part of the mandrel. The tapering shape of the latter facilitates the slipping off of the material during the pressing operation. Tensive strain on the mandrel is entirely absent by reason of the point with which the mandrel is provided. The material to be pressed is on entering the matrix compelled to move in front of the mandrel more or less transversely to the direction of pressure (Fig. 7) and by this means exerts a rearward thrust on the mandrel.

The point 11 may be of non-circular, prismatic or angular section, and may be provided with longitudinal grooves ribs or projections. There may be used in connection therewith a matrix, the aperture of which corresponds at the entrance of the cross-section of the point 11, or is grooved or provided with projections, according to the shape of the object to be produced. Figs. 8 to 16 show examples of tubes, the internal contours of which are due to the cross-sectional shape of the point, and the external contours to the cross-section of the matrix. The thickness of the outer tube wall depends on the more or less deep insertion of the point into the matrix.

To allow of rapidly and easily inserting a fresh disk 8 the chamber 4 is provided with a mouth-piece (Figs. 19 and 20) consisting of a part 12 and a guide channel or inserting funnel 13. The latter may be slideable with other parts of the press in front of the chamber 4. The disk 8 is inserted through the channel 13 and rests on the part 12 until the die 2 advances.

10 In order that during the pressing operation the matrix remains pressed firmly against the chamber 4, it is locked in position. The bolts 15 moved by hydraulically actuated pistons 14 (Figs. 2 and 3) move in guides in the matrix block 6 at opposite sides of the matrix holder 7. The latter may have recesses for the inserting of the bolts. In the construction shown the bolts engage behind a collar 16 of the matrix holder in the locking position, the abutment surfaces of the bolts being wedge-shaped; the corresponding surfaces of the collar may be inclined accordingly. By this means a firm lock is obtained with comparatively slight pressure, and even if the matrix is worn re-adjustment is unnecessary. Owing to the short path of the bolts between their end positions only a small quantity of water is required for actuating them.

30 The press is also provided with an abutment device which stops the die at the end of the pressing operation. This device consists of a buffer located between the chamber 4 and die holder. In the construction shown in Figs. 2 and 4 this buffer consists of ring segments 17 which project over the edge of the press chamber and are elastically held away from the latter. At the end of the stroke the foot or holder 18 of the die 2 abuts against the segments 17 and is thus elastically checked, its movement being completely stopped when the parts 17 abut against the chamber 4. The parts constituting the buffer must allow of a further advance of the die if the latter is used to expel the residue of the material from the press chamber when the rear end of the latter is free. For this purpose the parts 17 may be adapted to be moved apart, and they may be positively connected to the bolts 15 in order that the further advance of the die cannot take place until the matrix is unlocked. In Figs. 2 and 4 the parts 17 are shown mounted on pins 19 guided in hollow arms 20 laterally projecting from the bolts 15 and suitably prevented from rotating.

60 Figs. 17 to 21 show another construction, in which the ring segments forming the buffer are mounted on arms 21 guided by grooves in the end wall of the press chamber and connected by means of double-armed levers 22 (Fig. 19) to the prolonged piston rods 43 of the pistons 14 actuating the bolts 15. Fig. 17 shows the segments 17 in position to stop the die, and Fig. 19 shows them withdrawn.

One of the arms 21 may also be connected to the part 13 through which the press disks are introduced.

In the construction shown in Figs. 22 to 27 the abutments or ring segments 17 are fixed to the end wall of the press chamber, and a ring 23 rotatable on the die holder 18 carries suitable abutments 24 in the spaces between the parts 17. During the pressing operation the parts 17 and 24 are opposite each other, so that the advance of the die is checked and stopped at the proper moment. When the residue is to be expelled from the press chamber by means of the die the ring 23 carrying the abutments 24 is rotated so that the said abutments move past the parts 17. The rotation of the ring is limited by an abutment 25 fixed to the die holder and engaging an annular groove 26 in the rear surface of the ring 23. The rotation of the latter is preferably effected by means of an auxiliary cylinder 27, arranged for example on the main cylinder 28 (Fig. 22). The rod of the piston 29 working in the cylinder 27 may be connected to a bell crank lever 30 pivoted at 33 and engaging the bifurcated end of a lever 31 fixed to the ring 23. To reduce friction the ring 23 is mounted in a ball-bearing 32.

The residue adhering to the matrix in the chamber 4 at the end of the pressing operation, and expelled by the die in order to be detached from the matrix by hand with the aid of a chisel, may also be mechanically removed by means of a device shown in Figs. 1 and 2. A slide, for example a plate 34, extending to the matrix block, carries a driver consisting of a divided ring, the parts 35 of which are rotatable on hinges 36 and serve to embrace a tubular prolongation 37 of the matrix holder, provided with an annular groove. Behind the ring 35 there is provided on the fixed table plate 38 a cross-piece 39, into which is inserted a mandrel 40 coaxial with the matrix and with its point directed to the rear. The diameter of this mandrel is equal to that of the aperture of the matrix. The part 39 is movable, in order to give passage for the rearward movement of the ring 35. In the construction shown the part 39 is for this purpose hinged to the table 38 at 41 (Fig. 2).

Below the table 38 a tube 43 surrounded by a cylinder 44 is supported by bearings 42. The ends of the cylinder 44 are closed except for the passage of the tube, and the latter is provided with cocks 45 and 46 for the inlet and outlet of fluid under pressure. At its central part the tube carries a piston 49 which makes a tight joint with the inner surface of the cylinder and divides the interior of the latter into two chambers 47 and 48. At each side of the piston the tube 43 has apertures 50. Projections 52 integral with the cylinder extend through a slot 51 in the table and support a plate 34 (Fig. 1). When

the advance of the matrix and the pressed tube or the like is to take place, and the plate 34 has for that purpose been moved into the position shown in Fig. 1, the driver 35 is closed and the cross bar 39 turned back (Fig. 2). The water under pressure is admitted to the tube 43 at 45, and enters the chamber 47 of the cylinder 44, so that the plate 34 is moved toward the left. The driver 35 therefore moves the matrix out of the matrix block until the matrix is in or near the position indicated in the drawing by dotted lines. When the part 39 is moved into operative position water is admitted to the tube 43 at 46 and enters the chamber 48, so that the plate 34 is thrust toward the press again. The mandrel 40 is thus caused to expel the residue of material from the matrix. Thereupon the plate 34 is moved back to expose the mandrel 40 and the part 39 is turned back to expose the entrance to the matrix. Water is again admitted at 46 to move the matrix back into the press, in which it is locked by means of the bolts 15 for the next 25 pressing operation.

What I claim as my invention and desire to secure by United States Letters Patent is:—

1. In a press of the character described, 30 the combination with the press cylinder terminating in a matrix, of a plunger terminating in a perforate press disk and adapted to operate in the press cylinder, and a mandrel projecting through the plunger and the disk in spaced relation to the wall of the perforation in the disk.

2. In a press of the character described, 40 the combination with the press cylinder terminating in a matrix, of a plunger terminating in a perforate press disk and adapted to operate in the press cylinder, and a mandrel projecting through the plunger and the disk in spaced relation to the wall of the perforation in the disk, the perforation in the disk being enlarged at the rear.

3. In a press of the character described, 50 the combination with the press cylinder terminating in a matrix, of a plunger terminating in a perforate press disk and adapted to operate in the press cylinder, and a mandrel projecting through the plunger and the disk in spaced relation to the wall of the perforation in the disk; said mandrel being mounted to move in the plunger and of gradually increasing diameter from the front to the rear.

4. In a press of the character described,

the combination with the press cylinder, of a matrix arranged at one end of the press cylinder, a holder for said matrix having a reduced cylindrical portion intermediate of its ends, a block in which the matrix holder is movably mounted and having guides and bolts mounted to move in said guides and having semi-cylindrical end faces adapted to engage the reduced portion of the holder to lock the holder in position.

5. In a press of the character described, 60 the combination of a press cylinder, a plunger adapted to operate in the press cylinder, and a mouth-piece on the cylinder having a channel for the insertion of a suitable press disk on the plunger.

6. In a press of the character described, 70 the combination with the press cylinder and the plunger adapted to operate therein, of a buffer mounted directly in front of the press cylinder and adapted to arrest the advance of the plunger in the cylinder, and means for withdrawing said buffer to permit advance of the plunger.

7. In a press of the character described, 80 the combination with the press cylinder and the plunger adapted to operate therein, of a buffer consisting of a plurality of movable ring segments mounted in front of the cylinder and adapted to arrest the advance of the plunger in the cylinder.

8. In a press of the character described, 85 the combination with the press cylinder terminating in a matrix and the plunger adapted to operate in the cylinder, of means for locking the matrix in position in the cylinder, means for withdrawing said locking means, a buffer mounted to arrest the advance of the plunger in the cylinder, and a connection 90 between said locking means and said plunger whereby the plunger is withdrawn with the locking means.

9. In a press of the character described, 100 the combination with the press cylinder and the matrix mounted at one end of the cylinder, of means for withdrawing the matrix from the cylinder, and a mandrel adapted to be moved into the path of the matrix to expel residue from the matrix.

The foregoing specification signed at Berlin, Germany, this seventh day of June, 1907.

ARNOLD SCHWIEGER.

In presence of two witnesses—

HENRY HASPER,
WOLDEMAR HAUPT.
